CLAIM

The ornamental design for a mounting bracket for a portable electronic device, as shown and described.

DESCRIPTION

1. Mounting bracket for a portable electronic device

1.1 : Front

1.2 : Back

1.3 : Left

1.4 : Right

1.5 : Top

1.6 : Bottom

1.7 : Perspective

1.8 : Perspective

1.1 is a front view of a mounting bracket for a portable electronic device showing my new design; 1.2 is a back view thereof; 1.3 is a left view thereof; 1.4 is a right view thereof; 1.5 is a top view thereof; 1.6 is a bottom view thereof; 1.7 is a front perspective view thereof, and 1.8 is a back perspective view thereof.
